CLAIM

The ornamental design for an “electrical terminal block,” as shown and described.

DESCRIPTION

FIG. 1 is a perspective view of the top of an electrical terminal block showing my new design.

FIG. 2 is a perspective view of the bottom thereof.

FIG. 3 is a front elevation view thereof.

FIG. 4 is a right elevation view thereof.

FIG. 5 is a bottom plan view thereof.

FIG. 6 is a perspective view of the top of an electrical terminal block showing my new design with an alternate usage environment.

FIG. 7 is a perspective view of the bottom thereof.

FIG. 8 is a front elevation view thereof; and,

FIG. 9 is a right elevation view thereof.

The broken lines shown are for illustrative purposes only and form no part of the claimed design.
